UNITED STATES PATENT OFFICE.

NATHANIEL O. GOLDSMITH, OF CINCINNATI, OHIO, ASSIGNOR TO THE WEIR FROG COMPANY, OF SAME PLACE.

SWITCH-STAND.

SPECIFICATION forming part of Letters Patent No. 440,560, dated November 11, 1890.

Application filed July 31, 1890. Serial No. 360,496. (No model.)

To all whom it may concern:

Be it known that I, NATHANIEL O. GOLDSMITH, a citizen of the United States, and a resident of Cincinnati, in the county of Hamilton and State of Ohio, have invented certain new and useful Improvements in Switch-Stands, of which the following is a specification.

The object of my invention is to provide mechanism for turning the target on a three-throw switch-stand so as to maintain the same signal on two consecutive switch-movements, all of which will be fully set forth in the description of the accompanying drawings, making a part of this specification, in which—

Figure 1 is a plan view of my improvement in position for use. Fig. 2 is a side elevation of an upright three-throw switch-stand with my improvement attached thereto. Fig. 3 is a side elevation, partly in section, of a low-down three-throw split-switch stand containing my improvement. Fig. 4 is a top plan view of the gears for throwing the switch-staff in the first position. Fig. 5 is a similar view showing the position of the gears in the second position. Fig. 6 is a plan view showing the position of the gears in the third position. Fig. 7 is a perspective view of a modification adapted to the low-down stand shown in Fig. 3. Fig. 8 is a perspective view of one of the gears shown in Fig. 4. Fig. 9 is a perspective view showing the details of one of the parts. Fig. 10 is a plan view of the top of the switch-stand shown in Fig. 2.

1 represents the main tracks of a railway; 2 2, side switch-rails; 3 3, a second set of side switch-rails.

W represents the upright switch-stand, and C the crank-shaft.

40 B represents a collar in which the target-shaft A journals. It is provided with ears D, which are secured to the table E by screws or bolts.

F represents a lug on the ears D.

45 a is a pin in the target-staff A, which strikes against the lug to stop the rotation of the target-staff.

On the top of the crank-shaft C is mounted a mutilated gear 4, and on the bottom of the 50 target-staff is mounted a mutilated gear 5. In Fig. 4 the teeth of these gears are shown

in engagement. As the lever 6 is moved to turn the crank-shaft C, the engagement of the gears move the target-staff A into position shown in Fig. 5.

I represents the white vane on the top of the target-staff A, and G represents the red vane. Now moving said target-staff A a quarter of a revolution brings the red to the front and the white vane I at right angles thereto, exposing the red or danger signal. This is the position when the switch-rails H are moved to connect with rails 2. If, now, the lever 6 be turned another quarter of a revolution, the mutilated gears being in position shown in Fig. 5 at the beginning of the movement are out of engagement and the crank-shaft C moves around, carrying the switch-rails H into juxtaposition with the switch-rails 3, leaving the red signal exposed. The pin a strikes the lug F and stops the movement. When the gears 4 and 5 are brought into position shown in Figs. 5 and 6, it will be observed that the tooth 10 on gear 5 bears against the periphery of gear 4 and acts as a stop or lock to prevent the backward movement of the gears, thereby insuring the holding of the target in position. It prevents the rattle and jar of the train from moving the target-staff. The same engagement is shown in Fig. 6. 80 The point a, striking the lug F, locks the target-staff in position against a forward movement. When the lever 6 is turned backward, the target-staff is not affected until the gears are brought into position shown in Fig. 5, when 85 they are brought into engagement by means of the lugs 7 and 8, lugs 7 and 8 being preferably placed upon the under side of gear 4, so that said lug 8, engaging with the lug 7, brings the teeth of the mutilated gear into 90 mesh and causes the target-staff A to be turned into position exposing the white vane, when the said lever 6 has been turned back, bringing the gears into position shown in Fig. 4, and bringing the white vane to the front 95 and the red at right angles thereto.

In the low-down switch-stand, A' represents the target-staff.

C' represents the crank-shaft.

The beveled gears are mutilated and provided with lugs 7 and 8 and are of the same construction as those shown in Figs. 4, 5, and

6, except the teeth are beveled instead of spurred, and the lugs 7 and 8 are on the upper side of the gears.

The switch-stand shown in Fig. 2 is of the ordinary form and need not be described.

The construction of the three-throw low-down switch-stand is fully explained in Letters Patent No. 407,755, granted to Weir and Goldsmith July 23, 1889.

10 In the low switch-stand shown in Fig. 3 the lever 6 is shown in an upright position. When the bevel-gears are in the position shown in Fig. 5, with the red vane exposed, when it is moved over, say, to the right, the gears are carried into position shown in Fig. 6, and when said lever is moved, say, to the left the mutilated gears are carried into position shown in Fig. 4, thus exposing the red or white signal, as occasion requires for the side tracks.

15 Having described my invention, what I claim is—

20 1. In combination with a switch-stand having the crank-shaft C and the target-staff A, the

mutilated gears 4 5, provided with the lugs 7 and 8, co-operating to bring the mutilated gears 25 into intermeshing engagement and serving to turn the target-staff during a portion of the revolution, while allowing it to remain idle during the remainder of the revolution, substantially as described.

2. In combination with the switch-stand having the crank-shaft C and a target-shaft A, the mutilated gears 4 and 5, provided with lugs 7 and 8, and with the teeth 10 of gear 5 abutting the periphery of gear 4 for locking 35 the target-staff in position, said lugs co-operating to bring the mutilated gears into intermeshing engagement, substantially as specified.

30 In testimony whereof I have hereunto set my hand.

NATHANIEL O. GOLDSMITH.
